ARCHIBALD HALL-BROWN, OF PURLEY, AND EDWIN WALTER JONES, OF LINCOLN, ENGLAND, ASSIGNORS TO THE BABCOCK & WILCOX COMPANY, OF BAYONNE, NEW JERSEY, A CORPORATION OF NEW JERSEY

HEAT EXCHANGE DEVICE

Application filed June 24, 1927, Serial No. 201,080, and in Great Britain July 23, 1926.

Our invention more particularly relates to heat exchange devices comprising a rotary member having two groups of passages separated by walls and preferably alternating with each other, two different fluids of different temperatures flowing through the respective groups of passages. The heat exchange device also preferably comprises a stationary section. Our invention is particularly applicable to an air heater in which air is heated by waste gases, though it will, of course, be understood that our invention is not limited thereto.

Our invention will best be understood by reference to the accompanying drawings, in which we have illustrated a preferred embodiment of our invention, and in which Fig. 1 is a vertical section through a device embodying our invention and taken on the line 1—1 of Fig. 3 looking in the direction of the arrows; Fig. 2 is partially a plan view of the device with the top plates removed and partially a section taken on the line 2—2 of Fig. 1; Fig. 3 is a vertical section taken on the line 3—3 of Fig. 1; Figs. 4 and 5 are sections taken on the lines 4—4 and 5—5, respectively, of Fig. 1, and Fig. 6 is a plan view, partially broken away, of the top of the stationary air heater.

Like reference characters indicate like parts throughout the drawings.

Referring now to the drawings, 10 indicates generally a rotary heat exchange device which is preferably in the form of a fan or impeller, provided with hollow impeller blades 11 which may be formed by parallel plates preferably curved, as best shown in Figs. 4 and 5, and preferably attached at their outer ends to an annular member 12, and at their inner ends to an annular member 13, the fan comprising said annular members being secured to an operating shaft 28 by a plate 131. The impeller blades thus form two groups of alternating passages. Between the blades are the passages 14 of one group for one fluid such as air, and the hollow spaces within the blades form the passages 15 of the other group for another fluid, which is here shown as a waste gas. The blades are preferably tapered as best shown

in Fig. 1, so that their inner surfaces lie in a conical surface co-axial, in the embodiment illustrated, with a conical annulus 16 adjacent to the fan or rotary heat exchange device.

Assuming that the heat exchange device is used for heating air by means of waste heat gases, the air for the rotary section or member of the heat exchange device is supplied through a casing 17, suitable dampers 18 (Fig. 3) preferably being provided for controlling the air supply. The side of the casing 17 adjacent to the fan or rotary member 10 is formed with openings 19 through which air from the casing 17 enters the air passages 14 in the fan, flowing in the direction indicated by the arrows in Fig. 1.

The stationary section of the heat exchange device, in the embodiment illustrated, comprises a plurality of cells indicated generally at 20, each cell preferably being formed by two plates closely spaced, as shown in Fig. 2, and suitably closed at their edges, the air flowing through the cells, and the waste gases flowing between the cells. Distance pieces (not shown) may be fixed to the walls of the cells to maintain the required spacing of the cells in spite of any tendency to distortion due to heat influence. The cells, in the embodiment illustrated, are suitably attached to top plates 21 provided with slots or openings 22 registering with the cells, the plates 21 being supported by means which need not be specifically described.

Gas passages 23 are thus formed between each two adjacent cells. Heated gases from a furnace, or the like, enter the stationary part of the heat exchange device at 24, and flow over the cells through which the air is passing to the annular member 16 and enter the inner portion of the fan and are discharged in a general radial direction through the passages 15 to a passage 25 communicating with the stack 26.

In the embodiment of our invention illustrated, the fan or rotary member is actuated by a motor 27, to the shaft 28 of which is secured the fan or rotary member.

The cells 20 of the stationary heat exchange device are preferably each divided trans-

versely of the device by partitions 29 extending down into the cells, but short of the bottom thereof, as illustrated in Fig. 1. Air passages 30 are formed in the upper portion 5 of the device between the plates 21 and the roof 32, and vertical partition plates 31 are preferably provided which register with the partitions 29 in the cells, so that the air which is discharged from the passages 14 in the 10 fan flows over the annulus 16 to the passages 30, the air being compelled to flow downwardly into each of the cells and under the end of the partitions 29 upwardly to the next succeeding portion of the passage 30, and is 15 eventually discharged through the heated air outlet 33. The air, therefore, discharged from the fan to the passages is compelled to pass downwardly and upwardly through the cells in thin sheets or films interleaved with 20 films of hot gases separated from the air films by the thin vertical metal walls of the cells.

Elements of a scraper gear are indicated at 35, an access opening at 36, and a soot hopper 25 at 38.

The rotary member or fan constituting one section of the heat exchanger illustrated in our invention, produces effective heat transfer between the hot gases flowing through 30 the passages in the fan, and the air flowing through passages alternating with the passages through which the hot gases flow. Furthermore, the single fan serves to force both air and heated gases through not only the 35 fan or rotary member, but through the stationary section of the heat exchange device. The combination, therefore, is particularly effective since it not only promotes heat transfer in the fan itself, but increases the velocity 40 through the stationary heat exchange device, thereby increasing the heat exchange therein.

The fan being disposed at the cold end of the heat exchange apparatus, it is practicable to use a small-sized fan.

45 The arrangement is particularly applicable to a stationary heat exchange device where thin films of air are separated from thin films of the hot gases, thereby creating high resistance to the flow of gases there- 50 through, since the heat transfer roughly varies in proportion to the resistance of the flow of gases therethrough.

By supporting or suspending the plates or 55 walls of the stationary cells 20 from one end only and preferably from the upper end as illustrated, and leaving the lower ends, free, it will be noted that the walls are free to expand and contract without producing strains 60 in the metal of which they are formed.

We claim:

1. A heat exchange device comprising a rotary section and a stationary section, each of said sections having two groups of passages separated by walls, the passages of one

group alternating with those of the other group, the rotary section being constructed and arranged to cause fluids having different temperatures to flow through the respective groups of passages of both of said sections. 70

2. A heat exchange device comprising a rotary section having two groups of passages separated by walls, the passages of one group alternating with those of the other group, said heat exchange device also comprising a 75 stationary section, the heated gases passing over said stationary section, and then through the passages of one group of said rotary section, and the air passing through the passages of the other group of said rotary section, and then over said stationary section. 80

3. A heat exchange device comprising a rotary section and a stationary section, each of said sections having two groups of passages separated by walls, the passages of one group alternating with those of the other group, the rotary section being constructed and arranged to cause fluids having different temperatures to flow through the respective groups of passages of both of said sections, 85 the rotary section being located at the cold end of said device. 90

4. A heat exchange device comprising a rotary member having an inner and outer conical surface and provided with two groups 95 of passages separated by walls, the passages of one group alternating with those of the other, one group extending from said inner conical surface outwardly through said rotary member, means for rotating said member, and means for conducting relatively hot and relatively cool gases to and from said passages. 100

5. A heat exchange device comprising a hollow vane fan provided with one group of 105 passages between the vanes and another group of passages through the vanes, said vanes being formed both inside and outside to propel the two fluids, while heat is being transferred from one to the other, and means 110 to prevent gases passing through said respective passages from commingling. 115

6. A heat exchange device comprising a stationary heat transfer device having two groups of passages separated by walls, and a hollow vane fan having one group of passages between the vanes and another group of passages through the vanes, the groups of passages of said fan communicating with the respective groups of passages of said stationary section, whereby said fan propels the gases through each group of passages of both said stationary heat transfer device and said rotary fan. 120

7. A heat exchange device comprising a rotary member having two groups of passages surrounded by walls, the passages of one group alternating with those of the other group, and means for causing different fluids 125 130

having different temperatures to flow through the respective passages, revolving parts of said rotary member bounding said passages on all sides so that the fluid that 5 flows through them is inclosed on all sides by revolving parts.
